PERSONAL UTILITIES RECEPACLE

Manuel Evans, Allentown, Pa.

Application April 10, 1942, Serial No. 438,514

1 Claim. (Cl. 206—29)

This invention relates to new and useful improvements in personal utility packages or books such as are used ordinarily for containing safety matches.

The principal object of the present invention is to provide a container or book for holding conveniently such items as needles, thread, toothpicks and also matches, such articles being frequently needed by travelers.

Another important object of the invention is to provide a holder of the character stated which can be divided when one of the items becomes exhausted in order to save the remaining items for future use.

Other objects and advantages of the invention will become apparent to the reader of the following description.

In the drawings—

Figure 1 represents a front elevational view of the book.

Figure 2 is a front elevational view of the book divided after, for instance, the matches have become exhausted.

Figure 3 is a side elevational view.

Figure 4 is an open elevational view.

Figure 5 is an open plan view showing the back and the toothpicks in place.

Figure 6 is an edge elevational view of the structure shown in Figure 5.

Figure 7 is a section on the line 7—7 of Figure 1.

Figure 8 is a section on the line 8—8 of Figure 4.

Figure 9 is a plan view of the blank.

Referring to the drawings wherein like numerals designate like parts, it can be seen that the book is formed from a T-shaped blank sheet 5, the head portion of this sheet defining flaps 6, 6 and an area 7. Just below the head portion of the blank are three fold lines 8, 9 and 10. This permits this area to be bent toward the head and then downwardly to define a trough a for the reception of a strip of matches 11 and a short card 12 on which different colored thread 13 and a needle 14 can be carried and this strip of matches 11 and the card 12 are held in place by wire fasteners 15, 15. The strip of matches 11 and the card 12 are secured in place in one side of the portion 7 of the head of the blank while at the opposite side and running longitudinally of the portion 7 is a strip of toothpicks 16 secured in place by a wire fastener 17.

It can now be seen that in order to complete the book, the flaps 6, 6 are folded in over the strip 16 of toothpicks, and then the portion 7

and inwardly folded flaps 6, 6 are swung to the right in Figure 6 so that it backs against an area 18 of the tail portion of the T-shaped blank.

The remaining portion of the tail portion of the blank is divided into a pair of flaps 19, 19 which are to be bent over the match strip 11 and the card 12 with their free ends disposed into the trough a as shown clearly in Figures 3 and 7.

- 10 The blank 5 has a scored line 20 extending from the slit 21 defining the flaps 19, 19, through the other end of the blank, so that when for instance the matches 11 have been used, and probably by this time also the toothpicks 16, the book 15 can be divided, by being torn along the scored line 20, thus permitting a person to retain the card 12 with the thread 13 and needle 14, or the other side of the book, of course, depending upon which side is used first.
- 20 Obviously, the flaps 6, which are scored, can be torn off when the supply of toothpicks 16 becomes exhausted.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

- An article holding book comprising an elongated sheet of material having an intermediate and opposite end areas, respectively, and a pair of flaps at opposite sides of one end area, respectively, said one end area being adapted to support two different articles on one face thereof upon opposite sides of the longitudinal center of the sheet and a third article on its opposite face, the pair of flaps being foldable over the third article, the intermediate area being foldable on said one end area over said flaps to form a cover for said third article, the other end area of the sheet being split in the longitudinal center of the sheet and forming a pair of flaps foldable on the intermediate area over the two articles, respectively, said one end area and the intermediate area being scored in alignment with said slit, and the first-mentioned pair of flaps when folded being spaced apart upon opposite sides of the longitudinal center of the sheet, whereby when the third article is removed, said book may be torn apart to provide two separate books for holding the two different articles.
